UNITED STATES PATENT OFFICE.

LOUIS S. ANSELL AND CORNELIUS SPEER, OF HUNTINGTON, WEST VIRGINIA.

WASHING-MACHINE.

1,115,373.

Specification of Letters Patent. Patented Oct. 27, 1914.

Application filed December 4, 1913. Serial No. 804,647.

To all whom it may concern:

Be it known that we, LOUIS S. ANSELL and CORNELIUS SPEER, citizens of the United States, and residents of Huntington, county 5 of Cabell, State of West Virginia, have invented certain new and useful Improvements in Washing-Machines, of which the following is a full and clear specification, reference being had to the accompanying drawings, in

10 which—

Figure 1 is a side elevation partly in section, showing our apparatus applied to a wash-tub; Fig. 2 is a plan view of the apparatus, the tub being omitted; and Fig. 3 is a 15 transverse vertical section, part of the large corrugated roller being broken away for the purpose of better illustration. Fig. 4 is a detail plan view showing the manner in which the cap plates are swung to one side 20 to take the parts out of engagement with the shaft of the main roller.

This invention has relation to that type of clothes washing apparatus in which the clothing is passed between a series of rollers 25 mounted upon a frame which is removably set upon the rim of the tub, the washing apparatus being connected to the wash-bench in such manner as to be swung upwardly and over to one side out of the way; and the 30 object of this invention is to improve and simplify the apparatus, as more fully hereinafter set forth.

In the drawings, *a* designates the base-board which is adapted to be removably and 35 adjustably affixed in the tub by means of clamps *b*, each of which consists of a hook or neck carrying a thumb screw *c* adapted to bear upon the outside of the tub and a depending part adapted to depend into the tub 40 and being provided with a flat plate *d* which is secured against the underside of the base-board *a*, this securing means consisting of a bolt *e* passing through a longitudinal slot in said plate *d*. Two of these clamps are attached to one end of the base-board and one 45 clamp at the opposite end. The bolt and slot connections with the board *a* enable the clamps to be adjusted inwardly and outwardly to accommodate tubs of different 50 diameters.

Affixed to the base-board *a* is a pair of wooden standards *f* and pivotally attached to the outer face of these standards are links or bars *g*. These outer ends are respectively 55 provided with a longitudinal slot *h*. Companion bars or links *i* pivotally connect the

bars *g* to the cross rod *j* of the wash-bench, these bars *i* overlapping the adjacent ends of the bars *g* and being provided with longitudinal slots *k*. The connecting means between each pair of bars is a clamp bolt *l*, by means of which and the slots *h* and *k* the washing apparatus may be properly adjusted in the tub, and be swung upwardly and backwardly out of the way when not in use. 60 When the washing device is adjusted and clamped to the tub, it is desirable that the clamp bolt *l* shall be tightened, so that the bars *g* and *i* serve to assist in bracing the apparatus properly in the tub. 65

Journaled in bearings in the pedestals or standards *f* is the shaft of a large corrugated roller *m*, such shaft being extended at one end to form an operating crank *n*. Under this roller is mounted in the standards a 70 series of five companion rollers *o*, the end rollers being preferably larger than the intermediate rollers. The corrugated roller is yieldingly pressed toward the smaller or bed rollers *o* by means of coil springs *p*, each of 75 which is mounted in a vertical slot in one of the pedestals *f* and normally tends to force a bearing block *q* against the shaft of the roller. Each bearing block *q* is attached to the lower end of a rod *r* which passes down 80 through the spring and each spring presses upwardly against a cap plate *s* mounted on top of the pedestal. The rod *r* passes through a hole in this cap plate and it is provided with a handle *t* of ring or other form, 85 by means of which the bearing block *q* may be pulled upwardly whenever it is desired to relieve the corrugated roller of the pressure of the springs. 90

It will be understood that in the operation 95 of washing the clothes, it is simply necessary to rotate the corrugated roller and pass the clothes between the same and the bed rollers.

When it is desired to remove the corrugated roller from the apparatus for the purpose of cleaning or repairing the same or the bed rollers, this may be done in a very simple manner by simply swinging the cap plates to one side, as shown in dotted lines 100 in Fig. 2 and in full lines in Fig. 4. To enable this to be done conveniently, one end of the cap plate is pivotally fastened by screw bolt *u* while the opposite end of the cap plate is clamped by a similar screw or 105 bolt *v*, this screw being passed down through an open notch in the inner edge of the cap 110

plate. With this construction, by simply loosening screw *v*, the cap plate may be swung around on the other screw (*u*) as a pivot, thus carrying the rod *r*, spring *p* and bearing block *q* out of the slot in the pedestal and far enough to one side to be out of the way of the ready removal of the shaft of the corrugated roller from the slots. It will be observed that when the parts are thus 10 swung out of the slots in the pedestal, the ring or head *t* at the upper end of the rod will prevent the rod from being detached from the cap plate and will hold the spring under compression.

15 Having thus described our invention, what we claim is:

In a machine of the type set forth, the combination of a base board and means for supporting it in a tub, pedestals or uprights 20 mounted thereon, each of which is vertically slotted, a series of bed rollers, a main roller mounted upon the bed rollers and having its shaft extended through said slots, a cap

plate mounted over each of said slots, one end of this cap plate being pivotally connected to its pedestal, so as to be capable of swinging to one side to uncover the upper end of the slot, rods carried by these cap plates, each rod carrying a bearing block adapted to bear upon the shaft of the main 30 roller, a spring surrounding each rod between its bearing block and its cap plate, means being provided at the upper end of each rod for holding the spring under compression, and means for detachably fastening the free end of each cap plate to the pedestal, for the purposes set forth.

In testimony whereof we hereunto affix our signatures in the presence of two witnesses this 2nd day of December, 1913.

LOUIS S. ANSELL.
CORNELIUS SPEER.
